UNITED STATES PATENT OFFICE.

HORATIO THOMAS, OF CHICAGO, ILLINOIS, AND LOUIS GARDNER BOSTEDO, OF ATLANTIC, IOWA, ASSIGNORS TO THE BOSTEDO PACKAGE AND CASH CARRIER COMPANY, OF ATLANTIC, IOWA.

CASH AND PACKAGE CARRIER.

SPECIFICATION forming part of Letters Patent No. 379,084, dated March 6, 1888.

Application filed September 28, 1887. Serial No. 250,913. (No model.)

To all whom it may concern:

Be it known that we, HORATIO THOMAS, of Chicago, in the county of Cook and State of Illinois, and LOUIS GARDNER BOSTEDO, of Atlantic, in the county of Cass and State of Iowa, have invented certain new and useful Improvements in Operative Devices for Cash and Package Carriers; and we do hereby declare the following to be a full, clear, and exact description of the invention, such as will enable others skilled in the art to which it appertains to make and use the same.

Our invention relates to improvements in the operative devices of package and cash carriers.

In the application of Louis G. Bostedo for a patent for an improved cash and package carrier, filed August 2, 1886, a patent for which was allowed April 14, 1887, a two-track system is employed, the tracks being located one above the other a proper distance in the same vertical plane. Cars with depending baskets for the transport of goods or money are used on these tracks. Stations are made at intervals, where elevators are arranged to permit the dispatching of goods or cash from these stations to a bundle-table or cashier's stand and the return of change or the wrapped bundles to the points where they were dispatched from. In this two-track apparatus cars are forwarded from the clerks' stations to the cashier's stand or bundle table on the upper track and returned to these several stations on the lower track. It is a peculiarity of our apparatus that switches or turn-outs are not necessary adjuncts. The use of these devices that are ordinarily employed to permit cars to pass one or more stations from the starting-point to the terminals of the tracks is obviated by certain devices connected with the elevators at stations. One of the provisions made to facilitate the continuous travel over the elevators, that if open would make a gap in the upper and lower tracks, consists in a free track-section placed in the lower track to bridge the elevator, this loose track-piece being adapted for removal by the elevator on its upward passage from the counter to line with either the lower or upper track.

Another necessary device consists of a car-arrester or "back-stop" that is provided to stop a car that is dispatched from a distant station when it in its passage approaches an open elevator the free track-piece of which has been removed by the elevator in the act of raising it to dispatch a car, and that reaches this open elevator before the descent of the elevator-frame restores the free track-piece to its normal position. This back-stop device is also shown in the joint application of L. G. Bostedo and H. Thomas, filed November 5, 1886, and for which a patent was allowed January 21, 1887.

It has been found that the back-stops or arresting devices heretofore employed are not perfect in operation, as it is possible that a collision of a moving car on the lower track in transit from a distant station to the cashier's stand may take place with the ascending elevator of an intermediate station. The same difficulty has been experienced in all two-track apparatus with regard to a car moving from the cashier's stand or bundle-table on the upper track, as there is liability of this car colliding with a rising elevator at an intermediate station; and, further, it has been seen that a safeguard is necessary to prevent the free track-section of a lower track at an elevator-station from doing injury in case it is accidentally dislodged and falls to the counter.

In view of these deficiencies in package and cash-carrier apparatus now in use we have invented simple and effective devices, one object of which is to provide improved back-stops for the lower and upper tracks that will automatically assume a position to arrest a car as soon as the elevator is raised slightly from its point of lowest depression near the counter, and before it removes the free track-section of the lower track above it, thus preventing a collision of the moving car with the rising elevator on either the lower or upper track.

A further object is to so secure the free track-section of the lower track that, while it will be allowed free legitimate detachment from its position by the upwardly-moving elevator, it will be prevented from falling upon

the floor or counter, and thus avoid the contingency of accident to persons or things below it.

A further object of our present invention is to provide an improved means of connecting the basket or package-receptacle to the transporting-car so that the center of weight of the load in the basket will be automatically brought directly beneath the center of the track to compensate for unequal distribution of weight in the basket or freight-receiver.

A further object is to construct the cash and package transporting device so that an elastic cushion will be interposed between the car

proper and the freight-receptacle to neutralize the shock incurred in suddenly arresting the car and its heavily-loaded freight-holder at any point on the line of track or at its terminals.

With these objects in view our invention consists in certain features of construction and combinations of parts that will be hereinafter described, and pointed out in the claims.

Referring to the drawings making a part of this specification, Figure 1 represents a front elevation of the tracks and elevator at a station. Fig. 2 is a side elevation of a car and attached freight carrier or basket. Fig. 3 is a cross-section of the car and basket attachment, taken on the line $x-x$, Fig. 2. Fig. 4 is a detached transverse section of the car and basket attachment, showing a modified form of this attachment. Fig. 5 is a detached view of a modified form of the spring-cushion employed to ease the shock when the car comes in contact with the stop. Fig. 6 is another modification of the shock-neutralizer for the freight-car and its basket.

In order to properly show the utility of our present improvements and give a clear description of their methods of action, we will describe such parts of a two-track cash and package carrier system as they enter into combination with.

A A represent the upper track, and A' A² the lower track, at an elevator-station.

B B are the well-hole frames, that afford a support to the track ends at a station and also provide openings sufficient for the free passage through the two tracks of the elevator-frame O, which is raised or lowered by the pull-cord W, that is adjusted over pulleys above the upper track. The elevator-frame O is slidingly supported by the perforated bosses P Q on this frame engaging the upright bars U U', which depend from the ceiling or other fixed point above the upper track.

The upper track, A, is provided at the station with an adjustable track-piece, B', that is hinged to the well-hole frame B to move freely on the pivot-points a a and allow the elevator-frame O to push it up when the frame O is raised to line with the upper track.

A free track-section, B', is made to fill the gap between the track ends that are secured to the well-hole frame B of the lower track, A' A². On the side of the well-hole B of the lower track near A² the back-stop is located.

This consists of a rigid bar, E', that is pivoted to the track on its rear surface at G', and is bent to form an offset at F' F², the portion F³ 70 of this bar extending toward the well-hole frame B.

The bar E' is adapted to support the buffer-rod C, that is surrounded by the spiral spring V, which acts as a cushion to the buffer-rod 75 and neutralizes any shock sustained by its head C', this latter portion being intended to engage a projection on the frame of a car approaching the elevator station when the bar E' is in a position to permit such a contact of 80 parts.

The bar E' and its buffer-rod are held in the position just described by the tension of the plate-spring H', which is made to bear on its top edge at a proper point to depress the head 85 C' of the buffer-rod C below the lower edge of the track A² and in a line with the abutment formed on a car-frame to engage it when the car comes with momentum from a cashier's stand or a bundle-table.

The vibrating lever K', that is pivoted to the inner surface of the well-hole frame B of the lower track, has its end K² extended over the portion F³ of the bar E', and in consequence its opposite end, K³, is depressed by the action 95 of the spring H'. The end K³ of the lever K' is in turn engaged by the extremity L² of the rocking arm L', the opposite end, L³, of which is made to bear upon the lower surface of the end M of the lever M' to raise it.

A chain or other flexible connection, N³, is attached to the end M of the lever M', and is downwardly extended to connect to a washer or other movable bearing, N², which is seated on and attached to a spiral spring, S, that encircles the supporting-bar U of the elevator. The chain-connection N³ is of such a relative length as to permit the spiral spring S to nearly seat itself upon the stop-block T', secured on the bar U of the elevator.

The construction of the back-stop mechanism of the upper track is identical with that of the lower track just described. It is located on the side of the elevator opposite to the lower-track back-stop, and has a chain, N, or other flexible connection extended to engage the pivoted arm M', which is loosely secured to the rear face of the well-hole frame of the lower track, and from thence downwardly, to be attached to the washer N⁴ and its spring S', that is made to surround the bar U' of the elevator near the supporting-block T, that, in conjunction with its fellow block T', furnishes a base on which the elevator-frame O rests when it is in a lowered position near the counter.

In operation the lowering of the elevator to rest near the counter conveniently for the deposit of goods or cash in its basket will compress the springs S S' by a contact of the blocks T T' with these springs. The tension or draft exerted by the weight of the elevator-frame O on the chains N N³ will be transmitted through the system of compound levers that have connection with the back-stop bars E' and E' of

the upper and lower tracks and raise the buffer-rods C C, so that their ends C' C' will be raised to allow cars to run freely on both the tracks when the elevator is in the depressed 5 position just mentioned.

When a car with its attached loaded basket is to be forwarded from a clerk's station to the cashier's stand or bundle-table, the elevator-frame O is raised, and it will be seen that a few 10 inches rise of this frame will release the compression of the springs S S', and in consequence the tension of the springs H' H will be exerted to instantly throw down the buffer-rods of the back-stops E' E', thus providing an arrester for 15 cars moving on either track until the elevator is again lowered to line with the lower track.

It should be further explained that the lower boss, P, of the elevator-frame O is made to project laterally beyond the outer surface of 20 the upper boss, Q, of the same frame on the side of the elevator adjacent to the back-stop E' of the lower track A², this provision being made to allow the upper boss to clear the end M of the lever M' and cause the lower boss, 25 P, to bear on this end of the lever M' when the elevator-frame is lowered to line with the lower track. It will be apparent that this arrangement of the relative parts just described will elevate the free ends of the buffer- 30 rods of the back-stops on the lower and upper tracks. The latter-named stop is operated to clear the upper track by the engagement of the boss P, that extends to abut on the inner end, 1, of the lever M' and depress it, this depression effecting the elevation of the free end 35 C' of the buffer-rod in an obvious manner.

The stop S⁴, that projects from the rear face of the well-hole frame B of the lower track near to the lever M', is provided as an abut- 40 ment for the end R of the lever M', to prevent an undue elevation of this lever by the spring H when this spring is allowed to exert its tensional strength on the back-stop bar E'. The lever M is thus retained in proper position to 45 engage the boss P of the elevator-frame.

In order to prevent the free track-section bar B² of the lower tracks, A' A², from falling to the floor in case it is accidentally dislodged from its normal position in the track-gap, or 50 off of the elevator-supporting bar when the latter-named bar lifts it out of place, the elevator-frame being on its upward passage, an arm, Z, is secured to the inner surface of this free track-section bar B², and is made to extend in- 55 wardly a proper distance to permit the ring Z', that is formed on its inner end, to receive the pull-cord W within it. By this provision the bar B² will, in case of its accidental displace- 60 ment, be restrained from falling below the elevator-frame O, as the pull-cord W will lead it to the top of this frame, where it will rest until it is restored to proper position in the track-gap, or on the supporting-bar provided for it on the elevator-frame, as is shown in our 65 patented cash and package carrier system.

In Figs. 2, 3, 4, 5, and 6 of the drawings im- 70 proved devices for facilitating and increasing

the effective action of the cash and package transporting car and its connected receptacle are shown. To afford a reliable action of the traveling car and its attached basket, it is necessary that the center of weight of the load placed in this basket be about in a direct line under the car-wheels, to insure the free travel of the car, and as it is not possible to so load the 75 car at all times that this will be effected by the location of the goods in the receptacle a provision must be made for the automatic regulation of the basket, to cause it to align the center of its load-weight to the center of the wheels of 80 the car. We have made such a provision that is simple and effective and that in its operation prevents an undue lateral vibration of the basket or goods-receptacle, which would be objectionable and hinder the proper travel of 85 the car. It is also important that an elastic cushion be provided that will absorb the shock of a sudden stoppage of the car, and in this appliance to the car it is of advantage to introduce the recoil-arrester at the points of attachment of the package receptacle or carrier to the car proper, so that a collision of the wheels or frame of the car with a rigid obstacle will not dislodge the contents of the basket or other package-receptacle that is connected to the car- 90 frame. 95

We will now describe appliances that will afford the regulation of weight of the car-load and absorb the shock of a sudden stoppage of the car. 100

In Fig. 2, I represents the frame of the car, to which the grooved wheels I' I' are revolu- 105 bly secured. The depending standards I¹ I² are connected below the wheels by the cross-bars d d'. The lower ends of the standards are enlarged to form bosses I⁴ I⁴, which are perforated to receive the horizontal bar J, that is secured to the upright hangers J' J' of the basket J² by insertion of its ends through the perforated upper ends of these hangers and compression of the set-screws b, to fix the bar J rigidly therein. Upon the bar J, prefer- 110 ably near its center, the arm I³ is placed and secured by set-screws f, to permit its proper adjustment with regard to the suspended basket J². This arm I³ is preferably provided with a bifurcated free upper end, the two limbs 115 2 3 of this forked end being located one each side of the cross-bar d'. (See Fig. 3.) The space allowed between the forked ends 2 3 is 120 such that a sufficient swing of the basket J² is permitted to insure the proper adjustment of its load to align its center of weight with the vertical plane of the wheels I' I' and not permit any objectionable side vibration of the 125 basket while the car is in transit on the track. Another and equivalent method of construct- 130 ing the arm I³ is to dispense with the forked ends 2 3, as shown in Fig. 4, and simply introduce the free upper end of the arm I³ between the cross-bars d d', the distance between these bars allowing a side play of the basket that is proper and restricting it from any improper lateral swinging movement. Between the

brackets $I^1 I^2$ and the boss of the arm I^3 the spiral springs $4 5$ are placed, these springs being made to encircle the horizontal bar J . (See Fig. 2.) The springs should be of proper tensile strength to cushion the loaded basket, and to do this properly the spring should be slightly compressed when inserted in place on the bar.

In Figs. 5 and 6 other modifications of the spring cushion device are shown. These are merely changes in the location of the springs, and their manner of operation is the same, with exception of that shown in Fig. 5. The spring 6 in this form of cushion has bearing ou but one side of the boss of the arm I^3 , and will therefore only cushion upon one end of the car.

We will revert to the back-stop device previously described to explain that the spiral springs $S S'$ are also designed to serve the purpose of an elastic cushion, to gently absorb the impact of a descending loaded elevator when other cushioning devices are not employed for this purpose. Further, we have illustrated and described this back-stop as applied to the Bostedo-Thomas system of cash and package carrying; but we do not wish to limit its operation to this system, as by a slight modification of details it may be applied to other two-track systems, the essential features being preserved, which consist in the provision of mechanism that will retain the back-stop in a position to permit travel on either track when the elevator is at rest below the lower track, the elevator holding this mechanism by its weight, so that a slight upward movement of the elevator-frame will release the back-stop and permit it to automatically assume a position to arrest a car running on the upper or lower track, this arrest being effected before the elevator has time to reach the lower track and open it.

Slight changes might be made in the constructive details of this invention without departure from the spirit or exceeding its scope; hence we do not desire to restrict ourselves to the exact forms shown; but,

Having fully described our invention, what we claim as new, and desire to secure by Letters Patent, is—

1. The combination, with a track, a back-stop, and an elevator-frame, of a movable spring-bearing indirectly connected to the back-stop and adapted to be engaged by the elevator-frame when the latter is at a point below the lower track, substantially as set forth.

2. The combination, with an elevator-frame and track, of a pivoted back-stop, a movable spring-bearing, and a flexible connection between the back-stop and bearing, whereby

when the elevator-frame is in its lowered position the back-stop is held clear of the track, substantially as set forth.

3. The combination, with an elevator-frame and track, of a pivoted back-stop, a bearing on which the elevator-frame rests when in its lowered position, a spring supporting said bearing, and a flexible connection between the bearing and back-stop, whereby when the elevator-frame is in its lowered position the back-stop is held clear of the track, substantially as set forth.

4. The combination, with an elevator-frame and a pull-cord, of a free track-section and an arm, the latter having an eye through which the pull-cord passes, substantially as set forth.

5. In a car for a cash or package carrier, the combination of two wheels, a frame-piece, two standards depending from this piece, two cross-bars secured to the standards, a goods or cash receptacle, two hangers attached to the receptacle, a bar adjustably secured to the hangers, and an adjustable arm adapted to engage the cross-bars and limit the side-swing of the basket or goods receptacle, substantially as set forth.

6. The combination, with a car, a rod slidably connected thereto, and a receptacle secured to said rod, of springs mounted on the rod and engaging the car-frame, substantially as set forth.

7. The combination, with a car, a rod slidably connected thereto, and a receptacle secured to the rod, of an arm secured to the rod, and a spring encircling the rod at a point between said arm and one of the depending standards in which the rod is mounted, substantially as set forth.

8. The combination, with a car having depending standards, a rod loosely mounted in said standards, and a receptacle secured to the rod, of an arm secured on the rod at a point between the standards, and springs located on the rod between the arm and standards, substantially as set forth.

9. The combination, with a car having depending standards, a rod loosely mounted in said standards, a spring on said rod, and a cross bar connecting the standards at a point above the rod, of a receptacle rigidly secured to the rod, and an arm adapted to engage the cross-bar, substantially as set forth.

In testimony whereof we have signed this specification in the presence of two subscribing witnesses.

HORATIO THOMAS.

LOUIS GARDNER BOSTEDO.
